UNITED STATES PATENT OFFICE.

ALEXANDER P. MOORE, OF CHICAGO, ILLINOIS.

DESIGN FOR A BOTTLE.

SPECIFICATION forming part of Design No. 22,370, dated April 25, 1893.

Application filed March 8, 1893. Serial No. 465,179. Term of patent 14 years.

To all whom it may concern:

Be it known that I, ALEXANDER P. MOORE, a citizen of the United States, residing at Chicago, in the county of Cook and State of Illinois, have invented certain new and useful Improvements in Designs in Bottles; and I do declare the following to be a full, clear, and exact description of the invention, such as will enable others skilled in the art to which it appertains to make and use the same, reference being had to the accompanying drawings, and to the letters of reference marked thereon, which form a part of this specification.

The leading feature of my design consists in a bottle combining in its form the representation of a railroad tank with roof and flue or chimney, the body of the tank having thereon representations of bands with fastenings.

In the drawing, which represent my designs for a bottle, A designates the body of a bottle in the form of a railroad tank, having the roof B as shown, and the neck and head C representing a flue or chimney. Surrounding the body A are bands D which have fastenings E thereon and on the representation of the roof is shown a segmental panel, on which letters, words or other characters may be formed if desired.

What I desire to claim is—

The design for a bottle as herein shown and described.

In testimony whereof I affix my signature in presence of two witnesses.

ALEXANDER P. MOORE.
